UNITED STATES PATENT OFFICE.

MICHAEL REDMOND, OF CLEVELAND, OHIO.

MACHINE FOR TRUING ENGINE CRANK PINS OR SHAFT-END BEARINGS.

Application filed May 26, 1924. Serial No. 716,005.

To all whom it may concern:

Be it known that I, MICHAEL REDMOND, a citizen of the United States, and resident of Cleveland, in the county of Cuyahoga and State of Ohio, have invented certain new and useful Improvements in Machines for Truing Engine Crank Pins or Shaft-End Bearings, of which the following is a specification.

10 My invention relates to improvements in machines for truing the crank pins of engines and the like, and it consists of the constructions, combinations and arrangements herein described and claimed.

15 An object of the invention is to provide a relatively small, hand operated machine which is readily attachable to the end of a crank pin to be trued, the machine being accurately sustained in the operating position by a single bolt which is screwed into the threaded part of a bore which forms part of the oiling system.

20 Another object of the invention is to provide a machine for the purpose described which makes the work of truing a crank pin or end of an axle relatively simple in that the use of elaborate machinery is not involved and further that the engine need not be dismantled to any great extent in order 25 to apply the machine.

Other objects and advantages will appear in the following specification, reference being had to the accompanying drawings, in which

30 Figure 1 is a side elevation of the improved crank pin truing machine.

35 Figure 2 is a detail section taken substantially on the line 2—2 of Fig. 1, but being confined solely to illustrating the stationary plate in reference to which the machine works.

40 Figure 3 is a vertical section of the machine portions being shown in elevation.

45 Figure 4 is a detail perspective view of the upper part of the rotatable casing which fits upon the stationary plate.

50 Figure 5 is a front elevation of the machine.

Figure 6 is a cross section on the line 6—6 of Figure 1.

55 Figure 7 is a detail cross section on the line 7—7 of Figure 5, showing the manner of mounting the star wheel tripper.

Figure 8 is a plan view of the machine.

60 Figure 9 is a detail cross section on the line 9—9 of Figure 3, illustrating one of the car-

riage slides and the associated tool post slide.

Figure 10 is a detail cross section on the line 10—10 of Figure 8.

Figure 11 is a detail side elevation of the 60 stationary plate all carried parts removed.

Figure 12 is a section on the line 12—12 of Figure 3, particularly illustrating the casting retaining ring.

Figure 13 is a detail perspective view of 65 one of the bearing blocks of the stiffening ring.

Figure 14 is a detail cross section on the line 14—14 of Figure 13.

Figure 15 is a sectional diagram illustrating the action of the finger on the carriage in pushing the tripper out of the path of the star wheel in order to automatically stop the movement of the carriage.

Figure 16 is a detail perspective view of 75 one of the tool post slides.

Reference is first made to Figs. 1 and 3 which show the machine in place upon the end of a crank pin C to be trued. The cutting action of the machine is similar to that 80 of a lathe, but unlike a lathe the work remains stationary while the machine turns. The circular plate 1 is stationarily secured to the end of the crank pin by means of a bolt 2 which is screwed into the threaded 85 bore 3 which forms part of an oiling system. This oiling system has no bearing on the invention, but the threaded bore which is a part thereof provides a convenient place at which to secure the machine.

90 A central hole 4 receives the bolt 2. This hole is surrounded by a circular flange 5 which provides a hub providing a partial support for the rotatable casing 6. The face portion of this casing has a circular opening 7 (Fig. 4) which has a working fit upon the hub 5. The peripheral flange 8 of the casing contacts and rides upon the periphery of the stationary plate 1. A ring 9 is secured to the flange 8 from the rear by means of screws 10 in order to retain the casing upon the stationary plate. The casing and all of its carried parts turn upon the stationary plate. A filler 9^a is interposed between the end of the crank pin 105 and the stationary plate 1 in order that the cut may be carried to the end of the crank pin. If desirable, the stationary plate may merely be made thicker, thus avoiding the use of the filler and accomplishing the same 110 purpose.

The turning is accomplished by means of

a gear 11 which is fastened to the front face 6 of the rotatable casing by means of screws 12. This gear has a central aperture similar to the opening 7 of the casing to receive and 5 turn upon the hub 5. A pinion 13 meshes with and drives the gear. The pinion is carried by a shaft 14 which has a non-circular end 15 (Fig. 8) to receive a crank 16 for turning by hand. The crank shaft has bearing 10 ing in a boss 17 carried by an arm 18 which extends from and is a part of the hub 5.

Turning of the crank 16 in the clockwise direction (looking at the machine in Figure 5) causes the gear 11 and the entire truing 15 machine to turn in the counter-clockwise direction. The rotatable casing 3 merges into diametrically opposite supporting enlargements 19 upon each of which carriage rail slides 20 are secured by means of screws 21 20 (Fig. 10). Contacting faces of the enlargements 19 and the slide rails are grooved at 22 and 23 to receive a key 24 for the purpose of keeping the rails in correct positions relative to the rotatable casing. The adjacent 25 front faces 6 of the casing are recessed at 25 to provide room for the star wheels 26 which are situated between the casing and the gear 11.

Inasmuch as both slide rails 20 and the 30 associated parts are identical the description of one will suffice for both, corresponding reference numerals being used in both instances. The rail 20 has a dove-tail rib 27 which provides the support for the slideable 35 carriage 28 which carries the tool post slide 29 (Figs. 6 and 9). This slide, like the carriage 28, has a dove-tail groove 30 (Fig. 10) receiving a corresponding rib 31 (Fig. 3) on the carriage 28 holding the slide in place. 40 The carriage 28 has a lug 32 which is threaded to receive the carriage feed screw 33. This screw has a swivel mounting in the head of the rail 20 which is provided by means of a collar 34 contacting the head 45 on the inside (Fig. 3) and the star wheel 26 which contacts the head on the outside.

The star wheel 26 is fastened to the front 50 end of the feed screw in any suitable manner. The adjacent part of the feed screw is smooth and has bearing in a hole in the head of the rail 20. The collar 34 is made integral with the screw and is in the nature 55 of a flange. The collar and feed screw engaging the head from opposite sides provide the swivel mounting for the screw. The screw is given periodic turns in the proper direction to gradually feed the carriage 28 forward toward the end of the crank pin C. The entire machine turns in 60 the meanwhile and a portion is cut from the crank pin by means of a suitable tool 35 which is ultimately carried by the slide 29.

A post 36 (Fig. 9) has a slot 37 receiving 65 the tool and a screw 38 by means of which the tool is clamped against a washer 39

next to the slide 29. The slide has a T-slot 40 receiving the corresponding T-head 41 of the tool post. The action of the screw 38 not only fastens the tool 35 in place but also clamps the T-head 41 against the slide 70 29. Radial adjustments of the slide 29 and consequently of the tool 35 are made by means of a slide screw 42 which, like the feed screw 33, has a collar or flange 43 engaging the inside of a portion of the carriage 28 and has a knurled head 44 engaging the outside of the frame portion thereby completing the swivel mounting of the screw. Upon turning of the screw the slide 29 is adjusted as stated. The screw passes through a lug 45 on the slide 29 and thereby feeds the slide back and forth.

Periodic turning of the feed screw 33 is accomplished by the engagement of the star wheel 26 with a tripper 46 which is mounted 85 upon a lug 47 which is pendant from the bearing boss 17 of the stationary plate 1. This tripper is so fixed upon the lug 47 that the free end stands in the path of the star wheel. Upon each engagement of the star 90 wheel with the tripper the feed screw 33 makes a one-sixth turn. Screws 48, which occupy slots in the tripper hold the tripper 46 in place at one end, the remaining fastening being taken care of by a stud 49 which passes through a slot 50 in the tripper and carries a nut 51 in order to make possible any necessary adjustment of the spring 52. The purpose of the spring is to so hold the 95 tripper 46 that it will stay in position each time it is pushed outward in successive movements by each of a pair of fingers 53 described farther down. The slots permit 100 this movement.

It is necessary to provide a support for 105 the otherwise free ends of the rails 20. To this end, use is made of a stiffening ring 54 which carries a plurality of channel shaped guides 55 of which each has a bearing block 56 (Figs. 3 and 13) with a shank 57 occupying 110 the channel. A slot 58 admits a screw 59 which holds the block in place. A set screw 60, protruding beyond a boss 61 on the periphery of the ring, provides for inward adjustment of the bearing block in 115 each case. The blocks 56 slide upon the crank pin C as the machine rotates.

Legs 62, extending forwardly from the stiffening ring 54, have slots 63 through 120 which screws 64 pass. It is by this means that the rails 20 are supported in position. The slots 63 are for the purpose of permitting outward adjustment of the stiffening ring in reference to the rails 20 which adjustment may be necessary under some 125 circumstances.

Mention has been made of the fingers 53 and their functions of displacing the tripper 46 from the path of the star wheels. This displacement occurs straight out or along 130

the axis of the tripper. Neither the finger 46 nor the tripper is intended to be bent. Each finger is composed of a strip of metal given a quarter turn at 65 (Fig. 15) so that the free end stands at right angles to the portion 66 which is fastened to a carriage 28 by means of a screw 67. The screw passes through a slot 68, the slot providing for adjustment of the finger. The free end 10 of the finger is upturned at 69, and at the proper time the beveled end of the finger engages the slightly rounded end 72 of the tripper 46, so that by successively pushing the tripper outward, a condition will be reached when the tripper will no longer project into the path of the star wheels 26. The turning of the feed screws 33 then stops. The slots in the tripper permit the displacing movement mentioned.

20 In reference to the recesses 25 in the supporting enlargements 19 of the casing 6 it is to be observed in Figure 5 that these are completed by complementary recesses 70 in the ends of the heads of the rails 20. This arrangement is necessary to provide a pocket, as it were, for each of the star wheels. In reference to the stiffening ring 54 it is to be observed in Figures 5 and 6 that diametrically opposite portions are bowed out at 71 to provide adequate space for the tool slides and carried parts which come directly underneath. This is particularly true when the cutting action begins and when the tool slides are started at the free extremities of the feed screws 33 (compare Figs. 3 and 5).

40 The operation may be readily understood from the following additional description. The truing machine is composed of the casing 6 with its peripheral flange 8, the plate 1 upon which the casing is held by means of the retaining ring 9, the rail 20 and the ring 54 which is fastened to the rail to aid in generally stiffening the structure.

45 All of the foregoing parts, with the exception of the plate 1 and the filler 9^a (if used) are rotatable, the rails 20 carrying tools 35 bearing against the surface of the crank pin C for the purpose of taking off a shaving and thus truing the surface.

50 Use is made of the threaded portion 3 of an oil bore in the crank pin to screw in a bolt 2 and thus secure the plate 1 to the end of the crank pin so that it will not turn. It is upon this plate and its carried hub 5 that all of the mechanism turns. This includes the stiffening ring 54 which carries bearing blocks 56 to serve as a steady rest and keep the machine central.

60 A crank 15 (Fig. 8) is the means by which the machine is operated by hand. Turning of this crank turns the pinion 13 and the large gear 11 with which it meshes. It is preferable to turn the crank 16 in the clockwise direction, although it may be turned in

a counterclockwise direction with equally good results so far as the operation of the machine is concerned. The tripper 46 extends back from the lug 47 on the boss 17 of the fixed arm 18 and each time one of the 70 star wheels 26 meets the tripper it is subjected to a one-sixth turn. The feed screws 33 are consequently similarly turned with the result that the carriages 28 (Figs. 6 and 9) are gradually moved forwardly to properly advance into the metal. Cutting to the very end of the crank pin is assured by appropriately adjusting the tools 35 at angles as the end is neared.

80 As soon as the cutting tools 35 come within a predetermined distance from the end of the crank pin the properly adjusted finger 53 will so engage and push the tripper 46 outward little by little so that the latter will be ultimately displaced out of the path of 85 the star wheels 26 and turning of the latter will not result. Turning of the crank 16 may be continued but the carriages will be advanced no farther. Inasmuch as the operator is supposed to watch the action of the 90 machine he will be informed by the fact that the finger 53 is pushing the tripper that it is time to cease operating the machine. The rugged construction of the machine and the balanced disposition of the parts provide a 95 mechanism which is very effective for the purpose intended. The foregoing rugged construction also prevents chattering or vibrating of the tools regardless of how heavy or light the cuts taken may be.

100 While the construction and arrangement of the improved truing machine as herein described and claimed is that of a generally preferred form, obviously modifications and changes may be made without departing from the spirit of the invention or the scope of the claims.

I claim:—

110 1. A machine for the purpose described comprising a circular plate having a hub, means by which the plate is rigidly secured to the article to be trued, a casing of such shape to engage both the periphery and hub of the plate, means secured to the casing for retaining it upon the plate, a tool, means 115 carried by the casing in respect to which the tool is movable, said means including a rail, means including a feed screw for moving the tool along the rail, means including a tripper which is supported in a relatively fixed position by said plate, means 120 including a star wheel carried by the feed screw for periodically engaging the tripper, and means supported by said fixed plate operating to turn the casing in respect thereto whereby to move said tool around said article and cause the aforesaid periodic engagement of the star wheel.

125 2. A machine for the purpose described comprising a plate having a hub, an arm

extending from the hub terminating in a bearing boss, means to rigidly secure the plate and its carried parts to the article to be trued, a casing shaped so as to contact both on the periphery and hub of the plate, means including a ring engaging the opposite side of the plate to retain the casing, a gear carried by the plate, a shaft journalled in the bearing having a pinion meshing with the gear to rotate the casing upon the plate upon turning of the shaft, a tool, means including a carriage supporting the tool in the working position upon the article, and means for feeding the tool as the casing is rotated.

3. A machine for the purpose described comprising a circular plate having a hollow hub, an arm extending from one side of the hub terminating in a bearing boss, a casing so shaped as to bear upon the periphery and hub of the plate, means including a ring secured to the casing and engaging the plate from the opposite side to retain the casing upon the plate in a rotatable position, means situated in the hollow hub for rigidly securing the plate to an article to be trued, a gear affixed to the casing also bearing upon the hub, a shaft journalled in the boss carrying a pinion which meshes with the gear to turn the entire casing upon turning of the shaft, a rail supported by the casing, a cutting tool, means which carries the tool including a carriage supported by the rail, means for advancing the carriage including a feed screw journalled on the rail, a star wheel carried by the feed screw, and means for periodically turning the feed screw during the rotation of the casing said means including a tripper mounted upon said bearing boss and engageable by the star wheel.

4. A machine for the purpose described comprising a circular plate having a hollow hub, an arm extending from one side of the hub terminating in a bearing boss, a casing so shaped as to bear upon the periphery and hub of the plate, means including a ring secured to the casing and engaging the plate from the opposite side to retain the casing upon the plate in a rotatable position, means situated in the hollow hub for rigidly securing the plate to an article to be trued, a gear affixed to the casing also bearing upon the hub, a shaft journalled in the boss carrying a pinion which meshes with the gear to turn the entire casing upon turning of the shaft, a rail supported by the casing, a cutting tool, means which carries the tool including a carriage supported by the rail, means for advancing the carriage including a feed screw journalled on the rail, a star wheel carried by the feed screw, means for periodically turning the feed screw during the rotation of the casing said means including a tripper mounted upon said bearing boss and engageable by

the star wheel, and means including a stiffening ring for supporting the otherwise free end of the rail, said ring having means slidably engaging the article to be trued.

5. A machine for the purpose described comprising a circular plate, means by which it is rigidly affixed to an article to be trued, means which is revolubly mounted upon the plate including a casing bearing upon the periphery of the plate and having diametrically opposite supporting enlargements, a rail secured upon each of the enlargements, means including a stiffening ring to which each of the rails is affixed at the otherwise free end, means carried by the ring to engage said article for support during revolution, tools, means including carriages slideable along the rails supporting the tools in cutting positions upon said article, and means including feed screws journalled upon said rails and engaging the carriages for periodically shifting them in respect to said article.

6. A machine for the purpose described comprising a circular plate, means by which the plate is immovably affixed upon an article to be trued, a casing rotatably mounted upon said plate which provides a bearing, said casing including a plurality of supporting enlargements each of which has a recess, a rail secured to each enlargement and having a registering recess, the two providing a pocket, a stiffening ring, means for securing each rail to the stiffening ring, said means being movable to permit adjustment of the ring in respect to the rails, means carried by the ring to ride upon the article during rotation thereof with the casing, tools, means including a carriage by which each tool is slidably mounted upon the respective rails, means for advancing each carriage along the rails including a feed screw swiveled upon the rails, means to turn the feed screw including a star wheel mounted thereon and occupying said pocket, and relatively fixed means supported upon the plate including a tripper which is periodically engaged by the star wheel.

7. A machine for the purpose described comprising a circular plate, means by which it is stationarily affixed to the article to be trued, a revoluble casing carried by the plate, means mounted on the plate for revolving the casing, a tool supported by the casing, means carried by the casing for advancing the tool, said means including a feed screw having a star wheel, means including a tripper carried by the stationary plate which is periodically engaged by the star wheel during the rotation of the casing to turn said feed screw, means advancing with the tool to ultimately engage and displace the tripper from the path of the star wheel and thereby stop further advancement of the tool, and means by which the tripper

is so mounted as to permit said displacing movement.

8. A machine for the purpose described comprising a circular plate, means by which it is stationarily affixed to the article to be trued, a rotatable casing carried by the plate, means supported by the plate for turning the casing upon the plate, a tool, a tool post and slide supporting the tool, a carriage upon which the former are mounted, a rail carried by the casing along which the carriage is slideable, means for advancing the carriage including a feed screw having a star wheel, means supported by the stationary plate including a tripper which is periodically engaged by the star wheel to turn the feed screw and advance the carriage, means forming part of the mounting of the tripper permitting a pushing movement, and means carried by the tool slide including a finger for successively engaging and displacing gradually the tripper from the path of the star wheel to ultimately stop the turning of the feed screw.

25 9. A machine for the purpose described comprising a circular plate having a hub, an arm integral with and extending from the hub, a bearing boss carried by the arm having a pendant lug, means passing through the plate at the base of the hub to secure the plate stationarily to an article to be trued, truing means rotatably mounted on the plate including a cutting tool, means for advancing the cutting tool axially of the work during rotation including a feed screw having a star wheel, a tripper which is periodically engaged by the star wheel to thereby impart a turn to the feed screw, means including a screw for fastening the tripper at one end to the lug, means by which the tripper is additionally but yieldably secured, said means including a stud passing through a slot in the tripper, a spring on the stud and a nut adjustable on the stud against the spring; and means carried by said boss arranged to turn by hand to rotate the truing means.

40 10. A machine for the purpose described

comprising a circular bearing plate, means by which said plate is stationarily mounted upon the article to be trued, cutting means including a tool, means by which said tool is carried both circumferentially and axially of said article in the cutting operation, said means including a casing which has rotatable bearing on the plate, means extending rearwardly from the casing including rails, a stiffening ring substantially at the extremities of the rails to which the rails are affixed, means extending inwardly from the ring including blocks bearing on the article, and means supported by the stationary plate for rotating the casing upon the plate together with all of its carried parts.

45 11. In combination with an article to be trued including a crank pin having a threaded axial bore forming part of a lubricating system, a circular bearing plate having a central hole, means including a bolt to pass through the hole and screwed into the threaded bore for the purpose of stationarily affixing the plate to said article, rotating means supported by the plate, rotatable means having bearing support on the plate and operated by said rotating means, a plurality of rails extending rearwardly from said rotatable means, a stiffening ring to which all the rails are adjustably affixed, said ring including inwardly extending channels, means adjustable in said channels including blocks having shanks, said blocks bearing and sliding upon the article as said rotatable means is turned, a carriage carried by each rail having a screw bolt and slide, a tool carried by the tool post bearing against the article, means for advancing the tool post slide in reference to the carriage and article, means for advancing the carriages along the respective rails including feed screws having star wheels, and means including a tripper fixed upon said stationary plate and periodically engageable by the star wheels to successively turn the feed screws.

MICHAEL REDMOND.
